UNITED STATES PATENT OFFICE.

FRANK C. SPENCER, OF CHICAGO, ILLINOIS.

SAFETY DEVICE FOR PUNCH-PRESSES, &c.

1,043,876.

Specification of Letters Patent. Patented Nov. 12, 1912.

Application filed August 28, 1911. Serial No. 646,467.

To all whom it may concern:

Be it known that I, FRANK C. SPENCER, a citizen of the United States, residing at Chicago, in the county of Cook and State of Illinois, have invented certain new and useful Improvements in Safety Devices for Punch-PresSES, &c., of which the following is a specification.

This invention relates to a safety device for punch presses and other machines having dangerous parts.

The primary object of the invention is to provide efficient means to prevent injury to operators of machines, the unprotected use of which is hazardous to the person.

Another object is to automatically control the operation of a protective device in accordance with a periodic or recurrent function of the machine.

20 These with further objects and advantages of the invention will be understood from the detailed description hereinafter set forth.

In the accompanying drawings, Figure 1 is a perspective view of one embodiment of my invention mounted on a punch press. Fig. 2 is a detached perspective view of the protective device together with the press-controlling mechanism by which it is actuated. Fig. 3 is a perspective view of a bracket for mounting the protective device on the frame of the machine.

In the drawings, numeral 5 indicates the frame of a punch press of well known construction and operation, 6 and 7 are the stationary and reciprocable coacting press members, respectively, and 8 is the controlling member by which the operator causes the press to act.

40 A gate or shield 9 is pivoted to the outer end 10' of an angular bracket 10, the inner end 10'' of which is fixed to the said frame 5. The gate 9 has a gear member 12 fixed thereto concentric with the pivot 13 on which the gate turns. Levers 14 and 15 coact between the gear 12 and the control rod 8 to govern the movement of the gate. The lever 14 is attached by pivot 16 to the outer or transversely bent portion of bracket 10 as at 17, and lever 15 is similarly attached by pivot 18 to the inner portion of said bracket as at 19. One end of lever 14 is provided with a rack segment 20 arranged

to coact with the said gear 12, and the other end coacts with lever 15 at a point adjacent the bend in the bracket. One end of lever 15 is longitudinally slotted to receive the control rod 8, adjustable collars 21 being attached to the latter immediately above and below the lever. The adjacent ends of these levers are arranged to coact as by means of a longitudinal slot 22 in the end of lever 15 and a longitudinally projecting pin 23 on the end of lever 15, said pin extending cross-wise in said slot, and fitting operatively therein. A U-shaped stop 24 is attached to the bracket 10 at 25 and limits the movement of the guard mechanism by means of the outstanding arms 24' above and below lever 15.

70 The gate 9 is segmental in shape and comprises a peripheral frame 9' of rigid material with a grating or screen 23 thereon. When the gate is raised or rotated to a horizontal position it gives the operator free access to the punch members 6 and 7; but when it is lowered, as when the part 7 is about to descend it is rotated downward to a vertical position in front of the said punch members.

80 The control rod 8 is pressed downward by foot power against the tension of the restoring spring 24 to cause the press to act, and through the said lever mechanism simultaneously to rotate the gate 9 downward 85 in front of the danger point where the parts 6 and 7 coact. The gate 9 thus serves to brush away the hand of the attendant in case he accidentally permits it to remain too long or too near the impinging punch parts. 90 It also prevents inserting the hand during the period of danger.

It is usual to provide punch presses and similar machines with clutches arranged to be thrown in by means such as the rod 8, and arranged to be thrown out automatically when the punch actuating shaft has completed one revolution. When used with such a machine, the gate or guard 9 assumes the operative position before the movable press element, as 7, descends, the guard being automatically withdrawn by the spring 24 as the clutch is thrown out.

Having thus described my invention, I claim:

1. The combination with a machine hav-

ing a dangerous part the operation of which is periodic, of protective means actuated automatically in accordance with said periodic operation, said protective means comprising 5 a vertically disposed gate mounted on the front portion of said frame and arranged to move from one side of the operator's arms and transversely thereto into position in front of said dangerous part, whereby the 10 operator's hands will be pushed away from said dangerous part as the gate moves into operative position.

2. The combination with a machine comprising a frame and an operating mechanism having a dangerous part; of a vertically disposed gate pivoted to the front portion of said frame at a point above said dangerous part and arranged to swing in a vertical plane from a position at one side 15 of the operator's hands to its operative position in front of said dangerous part, and means for operating said gate.

3. In a device of the class described, the combination of a frame, a machine part supported thereby and having a cyclic operation, one phase of which is dangerous, a vertically disposed protective gate pivoted at its upper edge to the front of said frame at a point above said machine part, and 20 mechanism coöperatively connecting said machine part and said gate, said mechanism rotating the gate into operative position during the said dangerous phase and holding it away at other times.

35 4. The combination with a machine comprising a frame, operative mechanism mounted thereon, a part of which is at times dangerous, a controller rod at the side of said frame and arranged to start said 40 mechanism and a spring arranged to restore said rod; of protective means comprising a gate pivoted to the front of said frame and arranged to swing down in front of said machine part when the latter is in its dangerous 45 position, a lever pivoted to the front of said frame with one end operatively engaging said gate, a second lever pivoted to the side of said frame with one end engaging said controller rod, the opposite ends of 50 said levers operatively engaging each other, said levers causing the gate to swing downward when the said controller rod is depressed.

5. In a punch press in combination, a 55 stationary main frame, a vertically reciprocating member operatively mounted on the front side of the frame, said frame and reciprocating member being arranged for the mounting of coacting punch members thereon, means to control said reciprocating member, an angular bracket attached to one side of said main frame and extending forward and across the front of said reciprocating member, but out of contact there-

with, a movable gate member attached by 65 a pivot to the transverse portion of said bracket, and mechanism operatively connecting said gate and said means to control the reciprocating member, said mechanism comprising coacting levers, one pivoted on each branch of the said angular bracket, a pinion on said gate concentric with the said pivot, and a rack on the adjacent lever coacting therewith.

6. In a device of the class described, in 75 combination; a bracket arranged for mounting on the frame of a machine, said bracket comprising a flat bar having a central bend with the ends extending at an angle, a segmental gate member having a gear wheel 80 attached thereto at its apex, said wheel being pivoted to the outer extremity of said bracket, a lever pivoted centrally to the bracket arm adjacent said gate, said lever having a concave rack on its outer end arranged to engage the farther side of said pinion, a second lever pivoted centrally to the other or frame engaging arm of said bracket with one end extending adjacent 85 said frame, said levers having coactive engaging means comprising a longitudinal pin on the end of one lever and a corresponding longitudinal slot in the end of the other lever, said pin lying crosswise in said slot.

7. The combination with a punch press of 95 a vertically disposed gate pivoted at a point above the punch members; a pinion fixed to said gate concentrically with its pivot point; a pivoted lever; a toothed sector carried by said lever and meshing with said 100 pinion; and an operative connection between said lever and a movable part of the punch press.

8. In a device of the class described, the combination of a supporting bracket; a gate 105 pivoted thereto; a pinion fixed to said gate concentrically with its pivot; a lever pivoted on said bracket; a rack carried by said lever and meshing with said pinion; and means to form a connection between said 110 lever and a controlling member on the machine.

9. The combination with a machine of the character described, of a guard member pivoted in front of the dangerous portion 115 of the machine on a horizontal axis running above said dangerous portion and running from front to rear of the machine; and means automatically operated in advance of the actuation of said dangerous portion for 120 moving said guard member into guarding position.

10. The combination with a punch press of a vertically disposed gate pivoted in front of the punch members on a horizontal 125 axis running above said members from front to rear of the machine; a transversely extending lever at the front of the machine

1,043,876

8

having an operative connection with said gate for swinging the latter; and a second lever running in a direction from front to rear of the machine, said second lever engaging the first lever and being arranged to be operated by the controlling rod of the punch press.

In testimony whereof I affix my signature in the presence of two witnesses.

FRANK C. SPENCER.
